(57) **CLAIM**

The ornamental design for a laser oscillator, as shown and described.

DESCRIPTION

FIG. 1 is a front right side perspective view of a laser oscillator, showing our new design;

FIG. 2 is a rear left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a cross-sectional view thereof, taken along line 9-9 of FIG. 3; and,

FIG. 10 is a cross-sectional view thereof; taken along line 10-10 of FIG. 3.

The broken lines in the drawings illustrate portions of the laser oscillator which form no part of the claimed design.
